LIGHTER FOR BARBECUES, STOVES OR THE LIKE

Helen M. Prada, 1103 Kathryn Road, and Arnold G. Prada, 1122 W. Nolcrest Drive, both of Silver Spring, Md.

Filed Nov. 12, 1959, Ser. No. 58,315

Term of patent 14 years

(Cl. D81—10)

Figure 1 is a view in front elevation of a lighter for barbecues, stoves or the like showing my new design;

We claim:

The ornamental design for a lighter for barbecues, stoves or the like, as illustrated.
